UNITED STATES PATENT OFFICE.

OSCAR SODERSTROM, OF NEWARK, NEW JERSEY.

DESIGN FOR A PICTURE-FRAME.

SPECIFICATION forming part of Design No. 35,061, dated September 10, 1901.

Application filed June 8, 1901. Serial No. 63,816. Term of patent 14 years.

To all whom it may concern:

Be it known that I, OSCAR SODERSTROM, a citizen of Finland, residing at Newark, in the county of Essex and State of New Jersey, have invented and produced a new and original Design for Picture-Frames, of which the following is a full and complete specification, such as will enable those skilled in the art to which it appertains to make and use the same.

10 In the accompanying drawings, forming part of this specification, in which like numerals of reference designate corresponding parts in both views, Figure 1 is a front view of my newly-invented design for picture-frames, &c., and Fig. 2 is a side view of such frame looking toward the right of Fig. 1.

15 My design in its essential features consists of two rectangular frames 1 with an oval ornamentation 2 at the top surrounded by a rectangular border 3, carved with leaf-sprays and birds and provided at the top with the figure of a cherubim or angel 4. These rectangular plates are supported a short distance

from one another in the open-work frame, having double branch cross-like projections 25 6 and 7 of different heights, which projections 6 and 7 are alternately high and low. At the upper corners of the crosslets 8 and on the top is a circle of crosslets of different heights joined to the rectangular frame, bearing 30 at the center a cable 10, within which is a triangle bearing two clasped hands, above which is a heart.

Having thus fully described my invention, what I claim as new, and desire to secure by 35 Letters Patent, is—

The design for a picture-frame, as herein shown and described.

In testimony that I claim the foregoing as my invention I have signed my name, in presence of the subscribing witnesses, this 3d day of June, 1901.

OSCAR SODERSTROM.
